UNITED STATES PATENT OFFICE.

CHARLES F. PAIGE AND STUART H. ULLRICH, OF COLORADO SPRINGS,
COLORADO.

COMBINED MATCH BOX HOLDER AND SAFE.

SPECIFICATION forming part of Letters Patent No. 739,273, dated September 15, 1903.

Application filed November 17, 1902. Serial No. 131,659. (No model.)

To all whom it may concern:

Be it known that we, CHARLES F. PAIGE and STUART H. ULLRICH, citizens of the United States of America, residing at Colorado Springs, in the county of El Paso and State of Colorado, have invented certain new and useful Improvements in a Combined Match Box Holder and Safe; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to improvements in a combined match box holder and safe; and it consists of the features hereinafter described and claimed, all of which will be fully understood by reference to the accompanying drawings, in which is illustrated an embodiment thereof.

In the drawings, Figure 1 is a perspective view of our improved device shown in the open position to permit the insertion of a match-box from below. Fig. 2 is a vertical section taken through the same shown in the closed position and with a box of matches in place. This section is taken on the line 2, 30 Fig. 3. Fig. 3 is a rear elevation of the device.

The same reference characters indicate the same parts in all the views.

Let the numeral 5 designate the body of the device, formed with front, top, and side walls, (designated 5^a, 5^c, and 5^d, respectively.) The lower part of the device projects forwardly, as shown at 5^e, forming an auxiliary chamber communicating with the main chamber and open at the top to permit access for removing matches. The front wall 5^a is cut off or shortened at the bottom to allow the matches 8 in the box 17 to pass from the main chamber to the auxiliary chamber. The body 45 of the device is hinged at the top to the rear wall 5^b, as shown at 5^b. This is the only connection between the body of the device and the rear wall, and by virtue of this construction the body part is allowed to swing away 50 from the rear wall, as shown in Fig. 1. This rear part 5^b is secured to a suitable support,

as the wall of a room, to which a nail, a screw, or other suitable fastening device 6 having a head is applied. This rear part is provided with an opening 7 large enough to allow the head of the fastening device to pass through. From this opening leads a narrow horizontal slot 7^a to a narrow vertical slot 7^c. The slots 7^a and 7^c are of sufficient width to allow the shank of the fastening device to pass freely, 60 but are too narrow to allow the head of the fastener to pass. The vertical slot is in the center of the part 5^b, measuring horizontally. It is also above the vertical center, whereby the device will be stable when mounted on 65 the fastener 6.

To place the device in position, it is only necessary to place the back part 5^b in position to allow the fastening-head 6 to pass through the opening 7. The device is then 70 moved laterally to cause the shank of the fastener to pass through the slot 7^a into the slot 7^c. The gravity of the device will then cause it to assume the position shown in Fig. 1. To insert the match-box 8, it is only necessary to swing the body of the device upwardly, as shown in Fig. 1, to a horizontal or approximately horizontal position. The box of matches, open at the top, may then be placed in position, after which the body of 80 the device is lowered and some of the matches will pass into the auxiliary chamber 5^e, which will be kept replenished until all the matches in the box are used. The body of the device will then be raised, the old box removed, 85 and a full box substituted.

Having thus described our invention, what we claim is—

1. A combined match box holder and safe comprising a body part adapted to hold a match-box and having a front part protruding from the lower part of the device and forming an open auxiliary chamber communicating with the main chamber, and a plate forming one of the walls of the device, to which the body is hinged at the top, the said plate being adapted to be attached to a suitable stationary support.

2. A combined match box holder and safe comprising a back plate adapted to be secured to a suitable stationary support, a body part adapted to hold a box of matches, said

body part being hinged at the top to the back plate and arranged to swing away from the same and upwardly to permit the insertion of a box of matches, the said body part having an open, forwardly-protruding bottom part forming an auxiliary chamber communicating with the main chamber, the front wall of the device being sufficiently short to allow the matches to pass from the main to the auxiliary chamber, substantially as described.

3. A combined match box holder and safe comprising a back plate provided with an opening sufficiently large to receive the head of a fastening device, a narrow opening or slot extending horizontally from the main opening and communicating with a narrow vertical slot or opening, the main opening being adapted to receive the head of a fastening device and the slots communicating therewith being of sufficient width to allow the shank of the fastener to pass through pre-

venting the head from passing, a body part adapted to hold a box of matches, said body part being hinged at the top to the back plate and adapted to swing away from said plate to permit a box of matches to be inserted, the body of the device being provided at the bottom with a forwardly-protruding open part communicating with the main chamber, to permit the removal of matches, substantially as described.

In testimony whereof we affix our signatures in presence of two witnesses.

CHARLES F. PAIGE.
STUART H. ULLRICH.
